UNITED STATES PATENT OFFICE

168,508

COMBINATION COCKTAIL AND DINING ROOM TABLE OR SIMILAR ARTICLE

Howard P. Hodgman, Morganton, N. C., assignor to Drexel Furniture Company, Drexel, N. C., a corporation of Delaware

Application March 3, 1952, Serial No. 18,759

Term of patent 14 years

(Cl. D33—14)

To all whom it may concern:

Be it known that I, Howard P. Hodgman, a citizen of the United States, residing at Morganton, in the county of Burke and State of North Carolina, have invented a new, original, and ornamental Design for a Combination Cocktail and Dining Room Table or Similar Article, of which the following is a specification, reference being had to the accompanying drawing, forming part thereof.

Fig. 1 is a perspective view of a combination cocktail and dining room table or similar article, showing my new design, and arranged for use as a dining room table;

Fig. 2 is a perspective view corresponding to Fig. 1 with the side panels of the table top in lowered position;

Fig. 3 is a perspective view of the bottom of the table corresponding to Fig. 1;

Fig. 4 is a perspective view of the table arranged for use as a cocktail table;

Fig. 5 is a perspective view corresponding to Fig. 4 with the side panels of the table top in lowered position; and

Fig. 6 is a perspective view of the bottom of the table corresponding to Fig. 4.

I claim:

The ornamental design for a combination cocktail and dining room table or similar article, as shown.

HOWARD P. HODGMAN.
